1

This invention relates to the stripping of bobbins and, more specifically, to an apparatus for stripping waste yarn off flanged bobbins.

Waste yarn on a bobbin that remains as a residue at the end of a textile operation, or that is rejected as defective for some reason, must be stripped from the bobbin before the bobbin can be used again. Stripping can be done by back-winding, but this is a slow and expensive operation and it is preferable, if the nature of the bobbin permits, to strip the bobbin by cutting the yarn from it. Hand cutting by means of a knife calls for a certain degree of manual dexterity, which is apt to diminish, even with an experienced operator, as he becomes fatigued, and this is liable to result in accidental injuries. Moreover, the bobbins also are liable to be cut or scratched, and to need reconditioning by buffing and waxing operations which not only are expensive but also tend, in course of time, to impart to the bobbins so irregular a shape that they become useless.

It is therefore an object of this invention to provide an apparatus for stripping the waste yarn from flanged bobbins by cutting, the operation of which is more rapid than hand-cutting, less dependent on manual dexterity, and less liable to injure the operator or damage the bobbin.

According to this invention an apparatus for cutting waste yarn from flanged bobbins comprises a pair of flange-engaging blades for cutting yarn from a bobbin in the neighbourhood of the flanges, an intermediate blade adapted to co-operate with the said flange-engaging blades and to cut yarn from the bobbin between the flanges and means for oscillating said intermediate blade lengthwise of the bobbin and relatively to said flange-engaging blades.

The flange-engaging blades may have flat outer edges which engage the flanges of the bobbin without risk of damaging them, these edges meeting the sharpened inner edges of the blades at an angle so as to form points which can enter between the flanges and the yarn adjacent to the flanges. The blades can be pivotally mounted, and spring-urged outwards, away from one another, so that their flat edges and their points closely engage the inner surfaces of the flanges as the bobbin is pressed into engagement.

The intermediate reciprocating blade is conveniently in the form of a rectangular plate, with one long edge sharpened and lying parallel to the axis of the bobbin to be stripped. It is preferably mounted in overlapping contact with the flange-engaging blades, its end edges being suit-

ably sharpened to co-operate in a scissor action with the appropriately sharpened inner edges of the flange-engaging blades, for cutting the yarn near the flanges. The principal edge, the long edge parallel to the axis of the bobbin, is more acutely sharpened to engage and sever the yarn along the whole length of the bobbin barrel by reason of its reciprocating, slicing action. By adjusting the position of the blade so that the points of the flange-engaging blades project just beyond the line of its long edge, this edge can be held just clear of the bobbin so as to cut the innermost layer of yarn thereon without scoring the barrel or blunting the blade by engagement therewith. The points dig slightly into the surface of the barrel, but without substantially damaging it as by a score or scratch.

For the purpose of feeding bobbins to the blades of the apparatus, a storage chute can be provided, adapted to serve as a magazine for bobbins and to guide the bobbins accurately and in succession to a position above the blades, from which they can be pressed into engagement with the blades. In this position the bobbin may be located by a resiliently mounted cradle, which yields as the bobbin is pressed down and automatically raises the stripped bobbin clear of the blades when it is released. A pressing element, preferably foot-operated, can be provided to press the bobbin down, and may be combined with forwarding means which, when the pressing means are released after the stripping of the bobbin, urge the next bobbin into position so that it displaces the stripped bobbin into a suitably disposed receiver. By the use of suitably shaped and mounted flange-engaging blades, the apparatus can be readily adapted for the stripping of many different types of bobbin, whether with flanges having plane inner surfaces, or slightly coned inner surfaces, or with one flange plane and the other slightly coned.

By way of example one form of apparatus according to this invention, adapted for the stripping of bobbins of the type last mentioned, will now be described in greater detail with reference to the accompanying drawings in which:

Fig. 1 is a perspective view of an apparatus for stripping waste yarn off flanged bobbins.

Fig. 2 is a sectional side elevation of the apparatus shown in Fig. 1.

Fig. 3 is a front elevation of the blade assembly of the apparatus with parts broken away, and

Fig. 4 is a fragmentary view of the bobbin forwarding means.

For the convenience of a standing or seated

operator the apparatus is mounted on a table 11. Two front upright members 12 and two rear upright members 13 are bolted to the top of table 11 and, in conjunction with two horizontal side members 14 and two oblique bracing members 15 form a supporting framework. In the lower part of the framework are mounted a back plate 16 and a front cover plate 17.

The back plate 16 pivotally supports a pair of upwardly extending flange-engaging blades 18, 19, each in a separate vertical groove 20 in the back plate 16, the grooves 20 being cut to a depth such that the forward faces of the blades 18, 19 are level with the forward face of the back plate 16. The blades 18, 19 are loaded by a spring 21, supported on a rod 22, so as to be urged away from each other. The outer edge 23 of each blade is smooth and flat, for safe engagement with the inner surfaces of the flanges 24, 25 of a bobbin 26, and the inner edge 27 is sharpened by being bevelled on the rear face to a blunt angle suitable for exerting a scissor-like shearing action. The sharpened inner edges 27 meet the flat outer edges 23 at an acute angle so as to form points 28. These points 28, in the outermost position of the blades 18, 19, are separated by the distance between the inner faces of the flanges 24, 25 of the bobbin 26 at the edges of the flanges, so that the points 28 engage the flanges 24, 25 as the bobbin 26 descends on to them, and enter between each of the flanges 24, 25 and the yarn wound on the bobbin 26. In this outermost position, the smooth outer edge 23 of one blade 18 is at right-angles to the axis of the bobbin 26 so as to engage the flange 24 which has a plane inner surface, while that of the other blade 19 is inclined slightly inwards to match the conicity of the other flange 25. The blade 18 may be replaced by a blade like the blade 19, or vice versa, for stripping waste yarn off bobbins having either two conical flanges 25 or two plane flanges 24.

The front cover plate 17 is mounted parallel to the back plate 16 and spaced from it by a distance slightly greater than the thickness of an intermediate blade 29 which is disposed between them. The front cover plate 17 is secured to the back plate 16 by bolts 30 passing through vertical slots 31 in the front cover plate 17. The intermediate blade 29 is rectangular and is sharpened along its upper edge 32. It is mounted in face contact with the flange-engaging blades 18, 19 so that its short terminal edges 33, which are sharpened to a blunt angle, can co-act with the inner edges 27 of the flange-engaging blades 18, 19 in scissor fashion. The intermediate blade 29 is bolted to a carrier plate 34 which is supported on rollers 35, 36 and 37 with ball-bearing mountings whose stationary spindles 38 are eccentrically mounted in the back plate 16. The carrier plate 34, and the intermediate blade 29 which it carries, are reciprocated lengthwise by a pivoted link connection 39 driven by an eccentric pin 40 on the end of a rotating shaft 41. The carrier plate 34 moves in light frictional engagement with spring-loaded balls 42 let into recesses in the back surface of the front cover plate 17. Two rollers 43 are mounted on the carrier plate 34 and engage beneath the lower edge 44 of the front cover plate 17 so as to prevent the intermediate blade 29 from rising. By turning the eccentric spindles 38 of the ball-bearing rollers 35, 36 and 37, the height of the intermediate blade 29 can be adjusted, both initially and to allow for subsequent wear on sharpening, so that the upper edge 32 is just below the points 28 of

the flange-engaging blades 18, 19. The vertical slots 31 allow the height of the front cover plate 17 to be correspondingly adjusted so that the two rollers 43 on the blade-carrier plate 34 engage the lower edge 44.

Above the blades 18, 19 and 29 is a resiliently mounted cradle which supports each bobbin 26 during stripping. The cradle comprises two forwardly projecting fingers 45, each of which supports one of the flanges 24, 25 of a bobbin 26 so as to leave the barrel exposed below, and passes outside the flange-engaging blades 18, 19.

Behind the back plate 16 and descending obliquely to the level of the cradle fingers 45 is mounted a chute comprising two parallel spaced angle irons 46. The bobbins 47 awaiting stripping rest upon the chute which thus serves also as a magazine. The leading bobbin 47 on the chute is propelled by the weight of those behind into engagement with a pair of star wheels 48 mounted for rotation in a pair of brackets 49 above the blade assembly, the accidental rotation of the wheels 48 being prevented by the friction of their mounting.

The brackets 49 also support a cross member 50 on which is slidably mounted a plunger 50 which is movable downwards against the action of a pair of springs 51. The lower end of the plunger 50 carries a member 52 of inverted channel section for engagement with the barrel of the bobbin 26, some play being provided in the connection between the plunger 50 and the channel 52 to accommodate the conicity of the yarn winding, if any.

The feeding and pressing down of the bobbins 26 is effected by the working of a horizontal shaft 53 mounted at the top of the apparatus and parallel to the intermediate blade 29 on a pair of uprights 54 standing on the table 11. A foot pedal 55 at the base of the table 11 on which the apparatus stands is connected through a helical spring 56 to an arm 57 on the shaft 53, the spring 56 limiting the force that can be applied to the arm 57.

A bearing roller 58 mounted on a second arm 59 projecting from the shaft 53 depresses the plunger 50 against the bobbin barrel and forces the bobbin 26 downwards, against the resilient mounting 60 of the cradle fingers 45, into contact with the blades 18, 19 and 29. The flange-engaging blades 18, 19 enter between the faces of the flanges 24, 25 and the yarn on the bobbin 26, and co-act with the intermediate blade 29 as it reciprocates, so that the yarn is cut with a scissor-like action at the ends of the bobbin barrel and a slicing action at the centre. The points 28 of the flange-engaging blades 18, 19 dig slightly into the barrel of the bobbin 26, and prevent the barrel from being pressed into cutting engagement with the intermediate blade 29. A counterweight 61 is attached to the end of the arm 57 and serves to assist the springs 51 and 60 in the return of the horizontal shaft 53 to its original position following a bobbin stripping operation.

The two star wheels 48 each have four radially extending arms 62, and four corresponding axially projecting pins 63 on the inner faces of their bosses. The pins 63 are engaged by pivoted hooks 64 depending from a pair of further arms 65 which project from the horizontal rocking shaft 53. As the shaft 53 is rocked on depression of the foot pedal 55 the hooks 64 descend, and are urged by light springs 66 against the pins 63. When the pedal is released and the shaft 53

resumes its former position the hooks 64 engage and draw the pins 63 upwards, so that the star wheels are rotated through a quarter of a turn against the frictional resistance of their mounting. This rotation displaces the stripped bobbin 26 and allows the next following bobbin 47 to move down into stripping position. The stripped bobbins 26 are collected at the front of the apparatus and returned to the pin board, or other container from which they were withdrawn to be placed on the chute 46.

Having described my invention, what I desire to secure by Letters Patent is:

1. An apparatus for cutting waste yarn from flanged bobbins said apparatus comprising a pair of flange-engaging blades for cutting yarn from a bobbin in the neighbourhood of the flanges, an intermediate blade adapted to co-operate with said flange-engaging blades and to cut yarn from said bobbin between the flanges, and means for oscillating said intermediate blade lengthwise of the bobbin and relatively to said flange-engaging blades.

2. An apparatus according to claim 1 in which the flange-engaging blades have sharpened inner edges and flat outer edges which meet said inner edges at an angle so as to form points.

3. An apparatus according to claim 1 in which the flange-engaging blades are pivotally mounted and spring-urged outwards away from one another.

4. An apparatus according to claim 1 in which the intermediate blade has one long edge sharpened and lying substantially parallel to the barrel of the bobbin.

5. An apparatus according to claim 4 in which the intermediate blade is mounted in overlapping contact with the flange-engaging blades, the end edges of said intermediate blade being suitably sharpened so as to co-operate in a scissor action with the inner edges of said flange-engaging blades.

6. An apparatus according to claim 5 in which the position of the intermediate blade can be adjusted so that the points of the flange-engaging blades project just beyond its long edge.

7. An apparatus according to claim 1 comprising a resiliently mounted cradle adapted to locate a bobbin above the blades, to yield as the bobbin is pressed down on to said blades and to raise the stripped bobbin clear of said blades.

10. 8. An apparatus according to claim 1 comprising a pressing element adapted to press the bobbin downwards into contact with the blades.

9. An apparatus according to claim 8 in which the pressing element comprises an upwardly spring-urged plunger adapted to engage the barrel of a bobbin, and means for lowering said plunger so as to press the bobbin downwards.

15. 10. An apparatus according to claim 1 comprising bobbin-forwarding means adapted, after the stripping of a bobbin, to urge the next bobbin into position so that it displaces the stripped bobbin.

20. 11. An apparatus according to claim 10 comprising an upwardly spring-urged plunger adapted to engage the barrel of a bobbin, means for lowering said plunger so as to press the bobbin downwards into contact with the blades, and means for actuating the forwarding means in timed relationship with the lowering of said plunger.

HENRY EWING.
